SYSTEM OF CARRIER CURRENT
TRANSMISSION

Jan Maurits Douwes Dekker, The Hague, Netherlands, assignor to Associated Electric Laboratories, Inc., Chicago, Ill., a corporation of Delaware

Application April 25, 1936, Serial No. 76,382
In the Netherlands April 30, 1935

9 Claims. (Cl. 179—15)

This invention relates to improvements in carrier-current communication systems, and more particularly to systems for carrier-current transmission in cables.

5 In carrier-current transmission in cables it is desirable to locate a maximum number of channels in a given frequency range in order that the system may provide as many separate transmission channels as possible.

10 To effect this desired result, sharp band filters are a requirement; moreover, these filters have to be of relatively small band-pass width, in particular for the higher frequencies. The latter requirement necessitates accurate tuning of the elements and very low power factors, with the attendant design and economic difficulties.

By way of example, the frequency scale which was used in the Morristown experiment (see the Bell System Technical Journal for July 1933, pages 251—263) may be considered. The separation of the carrier frequencies in this case was 4000 cycles, and a band 2500 cycles wide was transmitted by each channel, the modulation-frequency band extending from 250 to 2750 cycles.

15 The single (lower) sideband method of transmission was used, the carrier being suppressed. If the theoretical band-pass width of each filter is assumed to be 2700 cycles, a space 1300 cycles wide remains between pass bands, which is less than 50 percent of the width of a transmission band. The attenuation within these spaces should be about 60 decibels, if the noise in a channel due to an adjacent channel is to be kept within bounds. (The noise resulting from such 20 inter-channel interference is not correctly referred to as "cross talk" because such noise is unintelligible.) In the Morristown system, it was possible to divide the frequency range between 0 and 39 kilocycles into 10 separate channels, thereby permitting the simultaneous transmission of 10 conversations.

It is an object of the present invention to provide a carrier-current transmission system which requires approximately half the number of filters which are normally employed, without diminution of the useful percentage of the frequency range.

25 Another object of the invention is to provide a carrier-current transmission system in which the filter requirements are much less stringent than in previously known systems.

An additional object of the invention is to provide a carrier-current transmission system which may be adapted to transmit modulation

25 frequencies up to twice the normal maximum value, without changes in the filters.

According to the invention the channels are grouped in pairs having common transmitting circuits when a passage is made through the 5 cable or other transmitting medium, the channels of each pair being so arranged that the low modulation frequencies of both lie at the limits of the pass band of the transmitting circuit, and each group of two channels is separated from the 10 adjacent groups by a single band filter. The distance between the carrier frequencies is made such that they substantially coincide with the limiting frequencies of the pass bands.

20 In practice it is particularly advantageous to locate the unused signal sidebands in the unused portions of the total available frequency range, a condition which may be realized by making the unused or attenuating portions of the range sufficiently wide. By applying the present invention, such an arrangement is possible without consequent diminution of the useful percentage 25 of the frequency range because of the double width of the pass and stop bands.

At the receiving end of the cable or other 25 transmitting medium the two sidebands in each pair of channels are supplied to two separate demodulators, each of which is supplied with one of the two corresponding carriers.

If care is taken to make each carrier sufficiently strong relatively to any residue of the other carrier which may be present, the low-pass filter following each demodulator will arrest 30 the undesired response coming from the other channel of the pair.

35 The principle of the invention, which consists in pairing off the speech channels in the manner indicated (with the higher modulation frequencies adjacent each other), may also be applied to a system in which modulation and de-modulation are effected in two steps in the manner of a superheterodyne receiver. In this case the transmission circuit for each set of two channels consists of an auxiliary modulator with a 40 band filter connected to its input, this auxiliary modulator transferring the set of two sidebands supplied to the filter to a given point in the frequency range of the transmitting medium.

The sidebands supplied to the input band filter 45 are derived from a pair of modulators, each one of which is supplied with one of the modulation-frequency signals and with a carrier having a frequency situated near a cut-off frequency of the band filter, the carrier frequencies and the

band-filter characteristic being the same for all pairs of channels.

In systems of the type contemplated herein, a receiver may be used in which the currents from the transmitting circuit are conducted along two different transmission paths, each of which is supplied with one of the corresponding carriers, and each of which includes a demodulator followed by low-frequency selective transmitting means.

The invention will be better understood by reference to the accompanying drawing, in which:

Fig. 1 is a diagrammatic representation of a conventional form of carrier-current transmission system;

Fig. 2 is a diagrammatic representation of a carrier-current transmission system in accordance with my invention;

Fig. 3 is a block diagram of a carrier-current transmission system in accordance with my invention;

Fig. 4 shows graphically the performance of a system according to Fig. 3; and

Fig. 5 is a diagrammatic representation of a carrier-current transmission system in accordance with my invention, in which modulation and demodulation is effected in two steps.

Referring to Fig. 1, the frequency range of a cable or other transmitting medium is shown as extending from 0 to approximately 39 kilocycles. This range is divided into 10 channels each of which is approximately 2500 cycles in width. The attenuating range between adjacent channels is about 1300 cycles wide and the carriers, which are represented by the short vertical arrows, are spaced at 4000-cycle intervals. The lowest channel carries ordinary modulation frequencies and therefore no corresponding carrier is shown. The representation of this figure may be taken as typical of known carrier-current transmission systems.

Fig. 2 represents the frequency range of a transmitting medium, extending from 0 to about 40 kilocycles. As shown, this region comprises 9 channels, 8 of which are combined in pairs, in accordance with the invention, in such a manner that their high modulation frequencies are substantially adjacent, the lower limits of the audio-frequency region lying near the cut-off frequencies of the respective transmitting circuits, which are connected to the transmitting medium. The transmitting characteristics of these circuits are schematically shown in Fig. 2 by the curves 1. The arrows 2 indicate the location of the carriers in the frequency range.

As will be evident upon comparison with Fig. 1, the system according to the invention provides a saving of about 50 percent in the number of filters required. Moreover, the suppression bands are twice as wide in the new system as in the old; this permits locating the sidebands not destined for transmission entirely in the suppression bands, while maintaining the same useful percentage of the entire transmitting range. By these means the suppression bands of both the sender and receiver band filters are made to contribute toward the suppression of undesired transmission and therefore of noise or so-called "cross talk".

The carriers may be suppressed more or less completely by the use of balanced modulators; the attenuation near the edges of the pass bands may also contribute to this suppression. The functioning of the system is not dependent on the strength of the transmitted carriers.

The arrangement of apparatus for a system functioning according to the scale division of Fig. 2 may be as shown symbolically in Fig. 3. At the transmitting end of line 3, modulators 21 and 22 are connected through band pass filter 23 to the line. Modulators 21 and 22 are supplied from audio-frequency sources 24 and 25, respectively, and additionally have supplied to them carriers I and II, respectively, as shown. Modulators 21 and 22 are arranged to suppress the carriers. At the receiving end of line 3, band filter 4 is shown connected to the line. Band filters 4 and 23 may, for instance, have the transmitting properties shown graphically in Fig. 2 at 1, a pass band being shown at a, and a suppression band at b. The sidebands passed by filter 4 are supplied to a pair of parallel transmission paths 5 and 6, which include demodulators 7 and 8, respectively. One of the respective carriers from a local source at the receiving end is supplied to one of these demodulators, the other carrier being fed to the other demodulator, a requirement being that the amplitudes of these carriers be sufficiently large with respect to any residual carrier which may have come through the band filter to minimize "cross talk". If this requirement is satisfied, the signal or modulation transmitted on one channel is obtained from the demodulator 7, and the signal or modulation of the other channel passed by the band filter 4 is obtained from the demodulator 8. Low-pass filters 9 and 10 connected to the demodulator outputs transmit only the desired audio-frequency range and suppress all undesired frequencies above this range.

The operation of the arrangement of Fig. 3 is illustrated in the graphs shown in Fig. 4. Fig. 4a shows the frequencies which are passed by the band filters 4 and 23. Block I represents the upper sideband transmitted by carrier I, and block II corresponds to the lower sideband of carrier II. Carriers I and II are not transmitted, and hence are indicated by broken lines. Fig. 4b shows the voice or audio frequencies which appear at the output of low-pass filter 9, corresponding with the upper sideband of carrier I and represented by block I. The audio frequencies which correspond with the lower sideband of carrier II are very weak at the output of demodulator 7 and hence do not appear at the output of filter 9. Therefore they are represented by dotted block (II). Similarly, Fig. 4c shows the voice or audio frequencies which appear at the output of low-pass filter 10, corresponding with the lower sideband of carrier II and represented by block II. Since these frequencies cover the same range as those represented by block I of Fig. 4b, block II appears in the corresponding position in Fig. 4c. The audio frequencies which correspond with the upper sideband of carrier I are very weak at the output of demodulator 8 and hence do not appear at the output of filter 10. Therefore they are represented by dotted block I. The curve 11 of Fig. 4c indicates the operating characteristics of filters 9 and 10.

Fig. 5 illustrates the application of the principle of the invention to a system in which modulation and demodulation are effected in two stages, in an analogous manner to the operation of a superheterodyne receiver.

As shown at the top in Fig. 5 a separate first modulator is provided for each channel. In order to obtain pairs of two adjacent sidebands the signals of one of the channels, which shall make

up such a pair, are modulated with the carrier d_0 in the first modulator 12, the other channel being modulated with the carrier d_0' in the second first modulator 13. The carriers d_0 and d_0' are situated respectively near the upper and lower pass-band limits of the band filter shown in the right-hand upper portion of Fig. 5, curve 14 being the attenuation characteristic of this filter.

10 To every set of two channels is assigned a set of modulators 12 and 13 and a band filter with the characteristic 14, the frequencies d_0 and d_0' as well as the characteristic 14 being identical for all the pairs; the corresponding band filters 15 are therefore also identical for all pairs.

15 A separate auxiliary modulator 15 is provided for each pair of channels, the sidebands passed by the band filter being modulated in this modulator with an auxiliary carrier d_n , which has a 20 different frequency for each set of two channels and which is suppressed by the modulator. The outputs of the auxiliary modulators 15 are connected to the line or other transmitting medium. As a result of the arrangement described the 25 pairs of channels will occupy the correct relative positions in the frequency scale of the transmitting medium; the steps leading up to this result are shown in the lowest graph of the upper half of Fig. 5, as well as the resulting positions 30 of the channels.

At the receiving end the transmission medium or line is provided with as many auxiliary modulators as there are pairs of channels. The auxiliary modulator 16 is supplied with the auxiliary carrier d_n and thus transposes one pair of sidebands within the pass band of a band filter 17. These filters are present in a number equal to the number of the pairs of sidebands. After having been demodulated to eliminate the auxiliary carrier d_n , the n th and the $(n+1)$ th sidebands are passed to the input of band filter 17. In the demodulators 18 and 19 the received currents from the output of the filter 17 are demodulated to eliminate the carriers d_0 and d_0' . In the outputs of these demodulators low-pass 45 audio-frequency filters are provided, the operating characteristics of which are shown in Fig. 5 at 20. The operation is such that the n th channel is obtained from one filter and the $(n+1)$ th channel from the other filter.

50 The frequencies of carriers d_0 and d_0' are preferably of such a value that they lie above the frequency range to be transmitted, as well as their sidebands and the carrier d_n ; if this is done there is no need for any further separate filtering means. An advantage of the system of Fig. 5 compared with known systems is that only half the number of auxiliary modulators and half the number of main carrier frequencies (d_n) are required. Against this the only disadvantage is 55 the need for two auxiliary carriers (d_0 and d_0').

As the amount of residual carrier received over the transmitting medium determines the degree of cross talk experienced between the adjacent channels it is desirable: first, to work with carrier suppression in the sending modulator; and second, that the filters effect a maximum attenuation of the carriers. The frequencies limiting the pass band of the filter should therefore 60 lie as close to the frequency band to be transmitted as possible, in order to obtain positive attenuation of the carrier. As, moreover, the frequency bands of a pair of channels are juxtaposed in such a manner that the portions containing the harmonics of speech (which represent

very little energy) are near each other, these bands may be approached quite closely without entailing serious difficulties in audio-frequency filtering.

65 The pass band of each filter is thereby made about twice as wide as in the known system. If the same number of channels is to be provided for in the same total frequency range of the transmitting medium, the same percentage separation remains, such that the same attenuation 10 is obtained if the number of filter elements is also the same.

70 As a consequence of the doubled band width the difficulties of accurate tuning of the filters are reduced, and additionally the electrical requirements of the filters become easier of realization.

75 An additional advantage of the system is that if occasion arises a musical program may be transmitted in lieu of a pair of channels, the networks being retained unchanged.

Having thus described my invention, what I claim is:

1. A carrier transmission system including plural sources of modulation; plural sources of carriers, said carriers being alternately spaced in frequency; modulators for combining each of said modulations with one of said carriers to produce plural modulated carriers each having upper and lower sidebands; transmitting filters 30 each connected to frequency-adjacent pairs of said modulators, said filters being adapted to suppress the carriers, the lower sideband of the lower-frequency carrier, and the upper sideband of the higher-frequency carrier in each of said 35 pairs; and unitary means for simultaneously transmitting the remaining pairs of upper and lower sidebands to a receiving station.

2. A carrier transmission system including plural sources of modulation; plural sources of carriers, said carriers being alternately equally spaced in frequency; modulators for combining each of said modulations with one of said carriers to produce plural modulated carriers each having upper and lower sidebands; transmitting 40 filters each connected to frequency-adjacent pairs of said modulators, said filters being adapted to suppress the carriers, the lower sideband of the lower-frequency carrier, and the upper sideband of the higher-frequency carrier in each of said 45 pairs; and unitary means for simultaneously transmitting the remaining pairs of upper and lower sidebands to a receiving station.

3. A carrier transmission system including plural sources of modulation; plural sources of carriers, said carriers being alternately spaced in frequency; modulators for combining each of said modulations with one of said carriers to produce plural modulated carriers each having upper and lower sidebands; transmitting filters each connected to frequency-adjacent pairs of said modulators, said filters being adapted to suppress the carriers, the lower sideband of the lower-frequency carrier, and the upper sideband of the higher-frequency carrier in each of said pairs; unitary means for simultaneously transmitting the remaining pairs of upper and lower sidebands to a receiving station; receiving filters at said receiving station each adapted to select one of said transmitted pairs of sidebands; two demodulators associated with each of said receiving filters; means for supplying to each of said demodulators a current corresponding in frequency to one of the suppressed carriers; and low-pass filters associated with the outputs of each of said 70 75

demodulators arranged to transmit only the frequencies of the original modulations.

4. The method of conducting plural communications in a single carrier transmission medium which comprises impressing said communications separately upon carriers alternately spaced in frequency throughout a frequency range, suppressing the carriers, suppressing alternate upper and lower sideband frequencies, and transmitting the remaining lower and upper side-band frequencies through said medium to a receiving station, the spacing of said carriers exceeding the frequency band occupied by each pair of said remaining sideband frequencies.
5. The method of conducting plural communications in a single carrier transmission medium which comprises impressing said communications separately upon carriers alternately equally spaced in frequency throughout a frequency range, suppressing the carriers, suppressing alternate upper and lower sideband frequencies, and transmitting the remaining lower and upper sideband frequencies through said medium to a receiving station, the spacing of said carriers exceeding the frequency band occupied by each pair of said remaining sideband frequencies.

6. The method of conducting plural communications in a single carrier transmission medium which comprises impressing said communications separately upon carriers alternately spaced in frequency to produce modulation of said carriers with resulting upper and lower sidebands, suppressing said carriers and alternate upper and lower sidebands so that the remaining alternate lower and upper sidebands constitute adjacent pairs of sidebands, the frequency limits of each pair corresponding to the lower modulation frequencies, and transmitting said pairs of sidebands through said medium to a receiving station, the spacing of said carriers exceeding the frequency band occupied by each of said pairs of sidebands.

7. The method of conducting plural communications in a single carrier transmission medium which comprises impressing said communications separately upon carriers alternately equally spaced in frequency to produce modulation of said carriers with resulting upper and lower sidebands, suppressing said carriers and alternate

upper and lower sidebands so that the remaining alternate lower and upper sidebands constitute adjacent pairs of sidebands, the frequency limits of each pair corresponding to the lower modulation frequencies, and transmitting said pairs of sidebands through said medium to a receiving station, the spacing of said carriers exceeding the frequency band occupied by each of said pairs of sidebands.

8. The method of conducting plural communications in a single carrier transmission medium which comprises impressing said communications separately upon carriers alternately spaced in frequency throughout a frequency band, suppressing the carrier frequencies, suppressing alternate upper and lower sideband frequencies, transmitting the remaining lower and upper sideband frequencies through said medium to a receiving station, removing any remaining residue of the suppressed upper and lower sideband frequencies, separating said remaining lower and upper sideband frequencies into pairs each consisting of an upper sideband and an adjacent higher-frequency lower sideband, supplying the previously suppressed carrier frequencies separately to each of said pairs, and demodulating each carrier and its associated sideband frequencies to reproduce said communications.

9. The method of conducting plural communications in a single carrier transmission medium which comprises impressing said communications separately upon carriers alternately spaced in frequency to produce modulation of said carriers with resulting upper and lower sidebands, suppressing said carriers and alternate upper and lower sidebands so that the remaining alternate lower and upper sidebands constitute adjacent pairs of sidebands, the frequency limits of each pair corresponding to the lower modulation frequencies, transmitting said pairs of sidebands through said medium, conducting each of said pairs separately to a pair of demodulators, supplying the previously suppressed carriers separately to said demodulators, and substantially suppressing all frequencies in the outputs of said demodulators except the modulation frequencies corresponding to said plural communications.

JAN MAURITS DOUWES DEKKER.
